LID COVER FOR THE SEAT OF A WATER CLOSET

Sondra Nagy and Bob Nagy, both of 67-25
Dartmouth St., Forest Hills, N.Y. 11374

Filed Mar. 7, 1966, Ser. No. 1,307

Term of patent 3½ years

(Cl. D4—5)

FIGURE 1 is a top plan view of a lid cover for the seat of a water closet illustrating our new design; FIGURE 2 is a bottom plan view of the lid cover; FIGURE 3 is a side plan of the lid cover; and FIGURE 4 is a front plan of the lid cover.

We claim:

The ornamental design for a lid cover for the seat of a water closet, as shown.
